UNITED STATES PATENT OFFICE.

JOHN T. MOAR, OF ALBANY, WISCONSIN, ASSIGNOR OF ONE-HALF TO FRED G. SHULTZ, OF ALBANY, WISCONSIN.

FILING-MACHINE.

No. 893,186.

Specification of Letters Patent. Patented July 14, 1908.

Application filed November 13, 1907. Serial No. 402,032.

To all whom it may concern:

Be it known that I, JOHN T. MOAR, a citizen of the United States, residing at Albany, in the county of Green and State of Wisconsin, have invented a new and useful Filing Machine, of which the following is a specification.

This invention relates to filing machines and its object is to provide an endless file 10 particularly designed for inside work such as finishing the inner faces of dies and punches.

Another object is to provide a file made up of sections of novel form and arranged in a novel manner so that filings and other particles can not become lodged between the sections and thus hold them out of proper alignment during the operation of the file.

Another object is to provide a file made up of sections so shaped as to produce a continuous unbroken surface at the point of use.

With these and other objects in view the invention consists of certain novel features of construction and combinations of parts 25 which will be hereinafter more fully described and pointed out in the claims.

In the accompanying drawings is shown the preferred form of the invention.

In said drawings: Figure 1 is a side elevation of a machine embodying the present improvements, a portion thereof being removed. Fig. 2 is an enlarged longitudinal section through a portion of the file and showing the joint therein. Fig. 3 is a face view 35 of a portion of the file. Fig. 4 is an enlarged transverse section through a part thereof.

Referring to the figures by characters of reference, 1 and 2 designate upper and lower wheels or drums on which is mounted a belt 40 2' preferably formed of a flexible strip of steel. This belt is seated throughout its length within grooves 3 formed longitudinally within blocks 4 constituting the file sections. Each block has its ends beveled 45 and lying in parallel planes and is fastened to the belt preferably by means of a screw 5 which enters the grooved face of the block adjacent one end. The blocks are all arranged so as to abut when in alignment so that their outer or working faces will be continuous and no spaces will be formed between them and within which filings or other particles can accumulate. The ends of the

belt 2' are engaged by one of these screws as indicated at 6 in Fig. 2 so that by removing said screw the two ends can be separated and the belt inserted through a hollow object the interior of which is to be filed. By lapping the ends of the blocks as shown and described said blocks become self-bracing 60 when in alignment so as to practically prevent sagging or giving when subjected to transverse pressure.

In use wheels or drums 1 are mounted in suitable supports and in Fig. 1 one form of support has been shown, the same consisting of a base 7 upon which the lower wheel is journaled and a bracket 8 in which the upper wheel is journaled, said bracket being carried by a standard 9. A work holding table 10 extends from the standard and between the wheels and has openings through which the file extends, and if desired, bracing or guide blocks 11 may be disposed back of the front portion of the file close to the table so as to further prevent the same from giving when the work is pressed against it. Also if desired a suitable rotary brush 12 may be disposed upon the machine for the purpose of brushing from the file any particles which might adhere to its working face.

When it is desired to operate the file the same is set in motion by any suitable mechanism, not shown, the parts being so located that the outer ply of the file will move 85 downward as indicated by the arrow in Fig. 1, and the ends of the sections 4 will be inclined downwardly and rearwardly. When work is placed on the table 10 and pressed against the file it will be successively contacted by the blocks or sections 4 and as the ends of these sections abut and are inclined in the manner shown and described a continuous unbroken face is presented to the work and the ends of the sections are prevented 95 from biting into the work as would be the case if they were rectangular and spaced apart. Should it be desired to use the file for inside work the ends of the belt 2 can be separated in the manner heretofore described and 100 said belt and the file sections inserted through the work after which the belt ends can be resecured together. It is of course to be understood that the file sections can be of any desired contour and can be used for different 105 classes of work. Any suitable means not

shown may be used in connection with the machine for blowing dust from the table 10 so that it will not interfere with the work.

What is claimed is:

5. 1. A file comprising a belt, and a plurality of longitudinally channeled abrading sections each secured adjacent one end to the belt, said belt being mounted within the channel and the ends of the sections being 10 beveled and disposed to contact when in alinement.
2. A file comprising a belt, a plurality of abrading sections having longitudinal channels in one face constituting seats for the belt, 15 each section being secured adjacent one end

of the belt and having its ends beveled, the ends of the adjoining sections being disposed to abut when the sections are in alinement to form a continuous working face, and means for securing the ends of the belt together, said 20 means constituting a fastener for one of the abrading sections.

In testimony that I claim the foregoing as my own, I have hereto affixed my signature in the presence of two witnesses.

JOHN T. MOAR.
